EMERGENCY ELECTRICAL CONTROL
DEVICEWilliam F. Eames, Westfield, N. J., assignor to
Westinghouse Electric Corporation, East Pitts-
burgh, Pa., a corporation of Pennsylvania

Application November 28, 1947, Serial No. 788,548

11 Claims. (Cl. 187—29)

1

This invention relates to emergency electrical control devices and it has particular relation to elevator systems having emergency release mechanism permitting operation of an elevator independently of safety interlocks associated with the elevator.

In electrical apparatus it is conventional practice in many cases to provide safety locks which prevent incorrect or hazardous operation of the apparatus. For example in an elevator system, it is conventional practice to provide each elevator door or hatchway door with a door switch. The door switch has contacts which are open when the associated door is open and which are closed when the associated door is closed. The door switches are connected in series for the purpose of preventing operation of the associated elevator when one or more of the doors are open. However, under certain emergency conditions, it is desirable to permit operation of the elevator despite the fact that one or more of the doors may be open. For this reason, it is the practice to provide the elevator with a manually-operable emergency release switch for permitting operation of the elevator when one or more of the doors is open.

A conventional emergency release switch may be mounted on an elevator car behind a frangible panel. In order to actuate the switch, it is first necessary to remove or break the frangible panel. Following such removal of the panel, the switch may be actuated to bypass the safety interlocks.

The removal of the frangible panel does not interfere with the normal operation of the conventional elevator system. If the doors are all closed, the associated elevator may be operated in the normal manner. For this reason, when the frangible panel has once been removed or destroyed, the elevator operator may continue to operate the elevator in the normal manner without requesting replacement of the frangible panel. Such operator is undesirable.

To illustrate the problem further, let it be assumed that a locking device for an elevator hatchway door fails mechanically and the door bounces open as the elevator car leaves the associated floor. The opening of the door switch stops the elevator car. However, by operating the emergency release switch, the elevator operator can return to the floor for the purpose of closing the door. Since he may then continue to operate the elevator car in a normal manner, the elevator operator may neglect to report the defective door to his building maintenance department. Consequently, the defective door re-

2

mains a source of danger to inquisitive or thoughtless persons.

In accordance with the invention an elevator system is provided wherein an emergency release switch is associated with a frangible panel. However, removal or destruction of the frangible panel prevents normal operation of the elevator system. The elevator can be operated only if the elevator operator continuously actuates the emergency release switch. Since such continuous actuation of the switch is tiresome, the elevator operator soon requests replacement of the frangible panel, and is required by his supervisor to explain the reason for the removal of the panel.

It is therefore an object of the invention to provide an improved emergency release device for electrical systems.

It is a further object of the invention to provide an elevator system with an emergency release switch wherein a frangible panel must be removed or destroyed to actuate the emergency release switch and wherein removal of the frangible panel prevents normal operation of the elevator system.

Other objects of the invention will be apparent from the following description taken in conjunction with the accompanying drawing, in which:

30 Figure 1 is a schematic view of an elevator system embodying the invention;

Figs. 2 and 3 are schematic views of portions of the system of Fig. 1 with parts shown in different conditions of operation, and

35 Fig. 4 is a view in sectional elevation of an electrical switch device suitable for the system of Fig. 1.

Referring to the drawing, Fig. 1 shows an elevator car 1 and a counterweight 3 therefor which are connected by one or more flexible cables 5 which pass over a sheave 7. The sheave 7 is secured to a shaft 9 which also carries the armature of a direct-current motor 11 and a brake drum 13 having suitable brake shoe mechanism 15 associated therewith.

For rotating the shaft 9 the armature of the direct current motor 11 is electrically connected across the terminals of the armature of a direct current generator 17. This generator armature is secured to a shaft 19 which also carries the rotor of an induction motor 21 and the armature of a direct current generator 23. The direct current generator 23 supplies direct current for energizing the control circuits of the elevator system and for energizing the fields of the gen-

erator 17 and the motor 11. Energy for the polyphase motor 21 may be derived from a suitable source of polyphase energy represented by phase conductors L1, L2 and L3.

Operation of the elevator system is initiated in a conventional manner by a car switch 25 which is mounted in the elevator car 1. (The position of the switch in the car is illustrated in dotted lines. For the purpose of depicting connections clearly, the switch is shown removed from the car.) The car switch initiates energization of suitable elevator control circuits 27 for controlling the energization of fields associated with the generator 17 and the motor 11 and the energization of solenoid mechanism for controlling the brake shoe mechanism 15. Since any conventional driving system may be employed for the elevator car 1, it is believed that a further description of the system is unnecessary.

As previously pointed out, elevator systems have various interlocks for preventing undesirable or hazardous operation of the elevator system. For example, in Fig. 1 an interlock relay 29 is provided which has a solenoid connected in series with door interlock switches for energization from a suitable source of direct current represented by conductors L4 and L5. Ordinarily, one door interlock switch would be provided for the elevator car and each hatchway door and the number of doors consequently would depend on the specific elevator installation.

For the purpose of discussion, it will be assumed that the elevator car 1 has four hatchway or corridor doors D1, D2, D3 and D4 which are located at the four floors served by the elevator car. Each of the elevator doors carries a contact 31 which engages a stationary contact 33 when the associated door is closed. When the door is opened, in the direction of the arrow, the contacts separate to open the associated circuit. Such door interlock switches are well known in the art. By inspection of Fig. 1, it will be observed that if any of the doors is open, the relay 29 cannot be energized to close its contacts.

Ordinarily, the relay 29 would be provided with contacts in the various car running circuits for the purpose of preventing operation of the elevator system when any of the doors is open. For the purpose of illustration, it is believed sufficient to indicate one set of contacts 35 which are connected in series with the car switch 25. Since the contacts 35 are open when the relay 29 is deenergized, it follows that closure of the car switch 25 cannot initiate operation of the associated elevator system unless all of the doors D1, D2, D3 and D4 are closed.

It will be recalled that in emergencies operation of the elevator system may be desired despite the fact that one or more of the doors may be open. To permit such emergency operation, an emergency release device 37 is provided which includes a pair of contacts 39 and 41 which are connected by a bridging contact 43. The contacts 39, 41 and 43 cooperate with conductors 45 and 47 to bypass the door switches associated with the doors D1, D2, D3 and D4. (The device 37 is located in the car 1 as shown in dotted lines. To facilitate illustration of the circuit connections, the device 37 is shown removed from the car 1.)

The bridging contact 43 is provided with an operating button 49 and has a rod 51 projecting therefrom to terminate in a head 53. A spring 55 engages the head 53 to urge the button 49 into engagement with a frangible member or panel

57. The panel 57 may be constructed of any frangible material which may be destroyed without damaging associated parts of the apparatus. For example, porcelain or glass are suitable materials, and glass ordinarily would be employed for the frangible panel. A hammer (not shown) may be located near the frangible panel to facilitate breakage of the panel by an operator.

If the emergency release switch device 37 comprised only the parts thus far specifically described, destruction or removal of the frangible panel 57 would not interfere with the normal operation of the elevator system. Consequently, an elevator operator may continue to operate his elevator without replacing the frangible panel.

In order to make it impossible to operate the elevator system normally following removal of the frangible panel 57, the emergency release device 37 is provided with an additional switch for interrupting the interlocking circuit containing the door switches. The additional switch includes two contacts 59 and 61 which are connected in series with the door switches. A bridging contact 63 normally establishes a connection between the contacts 59 and 61 to complete an energizing circuit for the relay 29 when the door switches are closed. The bridging contact 63 may be biased against the contacts 59, 61 or the head 53 by means of a spring 65. It will be understood that an energizing circuit for the relay 29 may be completed through either of two parallel arms. One of these arms comprises the conductor 45, the contacts 39, 41 and 43 and the conductor 47. The remaining arm comprises the contacts 59, 61 and 63 and the door switches.

The system of Fig. 1 represents the normal condition of the emergency release device. In this condition, the door switches are effective for controlling the energization of the relay 29.

When emergency operation is desired, the panel 57 is removed or broken, as illustrated in Fig. 2. Following breakage of the panel 57, the spring 55 forces the button 49 through the position normally occupied by the panel 57. The resulting movement of the bridging contact 63 by the head 53 opens the contacts 59 and 61 to prevent subsequent energization of the relay 29, through the door switches.

Let it be assumed that the condition necessitating operation of the emergency release switch results from the presence of an open door D4. In order to move the car under such conditions the elevator operator manually presses the button 49 against the bias of the spring 55 to close the contacts 39 and 41 (Fig. 3). During such movement of the button, the spring 65 permits suitable adjustment of the bridging contact 63. Since the contacts 39, 41 and 43 now bypass the open door switch of the door D4, the relay 29 is energized and the elevator car can be moved as desired.

By reference to Fig. 2, it will be observed that breakage of the panel 57 is accompanied by movement of both of the bridging contacts 43 and 63 away from their associated contacts. Consequently, the elevator operator cannot operate the car thereafter in the normal manner. If he desires to move the elevator car, he must always press the button 49 to close at least one of the 70 associated pairs of contacts. Since this is a tiresome act, the elevator operator soon requests replacement of the panel 57.

Although the operating mechanism for the emergency release device 37 illustrated in Figs. 1, 75 2 and 3 may be employed, somewhat different op-

erating mechanism is illustrated in Fig. 4. In Fig. 4, two contacts 59a and 61a are shown which correspond to the contacts 59 and 61 of Fig. 1. The contacts 59a and 61a are secured by machine screws 71 to a support 73 which may be constructed of a suitable insulating material, such as phenolic resin. The contacts 59a and 61a have associated therewith a bridging contact 63a which corresponds to the bridging contact 63 of Fig. 1. The bridging contact 63a includes a strip 75 of electroconductive spring material having at one end a contact 77 for engagement with the contact 59a and secured at its opposite end to an electroconductive arm 79. This arm has a tongue 81 which extends through an opening in the contact 61a to permit a pivoting movement of the arm about the opening. A pin 83 is secured to the contact 61a and extends through the arm 79. This pin has a washer 85 secured to one end for the purpose of compressing between the arm 79 and the washer a spring 87. By inspection of Fig. 4, it will be observed that the spring 87 biases the arm 79 in a direction to urge the contact 77 away from the associated contact 59a. The upper end of the arm 79 is bent to form a protuberance 89 which operates as a cam follower.

For actuating the bridging contact 63a, a cam 91 is secured to a shaft 93 which is mounted for rotation relative to the support 73. A crank arm 95 is secured to the shaft 93 for rotating the shaft and the cam as a unit.

A second bridging contact 43a is provided which corresponds to the bridging contact 43 of Fig. 1. The bridging contact 43a is similar in construction to the bridging contact 63a but is spaced therefrom in a direction parallel to the shaft 93. The bridging contact 43a has associated therewith contacts which are similar to the contacts 59a and 61a and cooperates with its associated contacts in the same way that the bridging member 63a cooperates with its fixed contacts 59a and 61a. For actuating the bridging contact 43a against the bias of its spring, a cam 97 is secured to the shaft for the purpose of engaging the protuberance or cam follower 99 of the bridging contact 43a. The support 73 may be secured to a base member 101 in any suitable manner, as by means of machine screws 103.

Rotation of the crank arm 95 is effected by a plunger 105 which is slidably disposed in an opening 107 formed in the support 73. The crank arm 95 carries a pin 107 which enters a slot 109 located in one end of the plunger 105. At its opposite end, the plunger 105 has secured thereto, a hollow button 49a which corresponds to the button 49 of Fig. 1. This button contains a spring 111 which urges the button 49a and its associated plunger to the left relative to the support 73, as viewed in Fig. 4.

The cams 91 and 97 are shaped to produce successive operation of the bridging contacts 63a and 43a. With the button in the position illustrated in full lines in Fig. 4, the cam 91 maintains the bridging contact 63a in bridging relationship relative to its associated fixed contacts. The bridging contact 43a, however, does not bridge its associated fixed contacts. These positions of the bridging contacts correspond to the positions of the bridging contacts 63 and 43 in Fig. 1.

If the spring 111 is permitted to move the button 49a from the intermediate position represented in full lines in Fig. 4 to a position wherein in the end of the button is represented by the broken line 113, the resulting movement of the

plunger 105 acting through the crank arm 95 rotates the shaft 93 in a clockwise direction, as viewed in Fig. 4, to release the bridging contact 63a. As the cam 91 is moved in a clockwise direction by rotation of the shaft 93 the cam releases the cam follower 89 and permits the spring 87 to urge the bridging contact 63a away from the fixed contact 59a. The resulting positions of the various parts of Fig. 4 correspond to the positions of the various parts of the device 37 in Fig. 2. It will be noted that in this condition, both sets of contacts of the emergency release device are open.

Should the elevator operator actuate the button 49a to the position wherein the end of the button occupies the position represented by the broken line 115, the resulting movement of the plunger 105 actuates the shaft 93 in a counter-clockwise direction. During the initial rotation of shaft 93, the cam 91 engages the cam follower 89 to move the bridging contact 63a into bridging relationship relative to its associated contacts 59a and 61a. The continued rotation of shaft 93 finally brings the cam 97 into engagement with its associated cam follower 99 to move the bridging contact 43a into bridging relationship relative to its associated fixed contacts. The cams may be designed to maintain both of the bridging contacts 43a and 63a in bridging relationship when the end of the button occupies the position represented by the broken line 115. The resulting positions of the parts correspond to the positions of the parts of the emergency release device 37 illustrated in Fig. 3.

The button 49a is maintained in its intermediate position by means of the member 57. As previously pointed out, the member 57 may take the form of a frangible panel, preferably constructed of glass. The panel 57 is secured to a control panel P by means of suitable machine screws 117 and clips 119. It will be understood that the emergency release device is located in the elevator car and that the elevator operator does not have access to the space between the control panel P and the base member 101 until he breaks the frangible panel 57.

In operation it will be recalled that the bridging member 63a would be connected in series with the door switches. Since this bridging contact is closed when the button 49a occupies the intermediate or normal position illustrated in full lines in Fig. 4, it will be appreciated that the elevator operator can operate his car in a normal manner by manipulation of the car switch 25 (Fig. 1). This assumes that the door switches are closed.

Should one of the door switches be open for any reason, the elevator operator can operate his car by initially breaking the frangible panel 57 to expose the button 49a. Upon destruction of the panel 57, the spring 111 promptly moves the button 49a to open both of the bridging contacts 43a and 63a. Under these circumstances, the elevator operator cannot operate his car.

To initiate operation of the car, the elevator operator presses the button 49a to close both of the bridging contacts 43a and 63a. This permits operation of the car following closure of the car switch 25 but such operation is possible only as long as the operator continues to press the button 49a. Since the continued pressure of the button is tiresome, the operator soon requests replacement of the frangible panel.

Although the invention has been described with reference to certain specific embodiments,

numerous modifications falling within the spirit and scope of the invention as possible.

I claim as my invention:

1. In an elevator control system, elevator door means, a control circuit including interlocking means responsive to an opening operation of the door means for interrupting said control circuit, and a first switch operable independently of the door means for interrupting the control circuit, a second switch operable for bypassing the interlocking means and the first switch, and operating means for the switches, said operating means being operable independently of the door means and being operable from a first condition wherein both of said switches are open to a second condition wherein the first switch is effective for completing the control circuit and wherein the second switch is ineffective for bypassing the interlocking means and the first switch, said operating means being operable to a third condition wherein both of the switches are closed.

2. An elevator control system as defined in claim 1 in combination with means urging said operating means towards the first condition, and releasable restraining means for restraining the operating means in the second condition.

3. An elevator control system as defined in claim 2 wherein the restraining means comprises a member having a frangible portion in the path of the operating means which may be destroyed readily to release said operating means.

4. In an elevator system, an elevator car having a control panel which includes a frangible portion, a control unit comprising an operating member separated from the interior of the elevator car by said frangible portion, biasing means yieldably urging said operating member into an intermediate position wherein the operating member engages the frangible portion, said biasing means being effective upon removal of the frangible portion for urging the operating member through the position normally occupied by the frangible portion towards a released position, said operating member being movable against its bias away from the frangible portion towards an actuated position, said control unit including a first switch and a second switch responsive to the position of the operating member, an elevator door including a third switch responsive to the position of the door, a control circuit including said first and third switches in series, the first switch being closed in the intermediate position of the operating member and open in the released position of the operating member, said second switch being open in the released and intermediate positions of the operating member and closed in the actuated position of the operating member, and means controlled by the second switch for bypassing the first and third switches.

5. In an electrical switch device, first switch means, second switch means, operating means for the switch means including an operating member operable from a first position wherein both of the switch means are open, to a second position wherein only one of the switch means is open, said operating member being operable to a third

position wherein both of the switch means are closed, means yieldably urging the operating member towards the first position, and releasable restraining means restraining said operating member in the second position, said releasable restraining means being releasable for permitting operation of said operating member between said three positions.

6. An electrical switch device as defined in claim 5 wherein the releasable restraining means comprises a frangible member, said frangible member being readily breakable without damage to the remainder of the switch device to release the operating member.

7. In an electrical device, a circuit having connected in parallel a normally-closed first arm and a normally-open second arm, a frangible member, control means responsive to removal of the frangible member for interrupting the normally-closed arm, said control means including manually operable means accessible only following removal of the frangible member for closing the normally-open arm, and yieldable biasing means for urging the manually operable means to the condition wherein the second arm is open.

8. In an elevator system, a door control circuit having first and second arms connected in parallel, a first switch and a door-operated second switch connected in the first arm, a manually-operated third switch connected in the second arm, said switches having open and closed conditions, biasing means urging the first and third switches into predetermined first conditions, and releasable retaining means for releasably retaining the first switch in a second condition under normal conditions of operation of the elevator system.

9. A system as claimed in claim 8, wherein the first switch and second switch are connected in series in the first arm, and the releasable retaining means comprises a frangible glass panel normally retaining the first switch in closed condition.

10. A system as claimed in claim 8, wherein the glass panel until broken prevents operation of the third switch.

11. A switch assembly comprising first and second switches having open conditions and closed conditions, said switches being biased towards open positions, and means including a frangible member preventing access to said switches for changing their conditions, said frangible member being positioned to retain the first switch in closed position until the frangible member is removed from its normal position.
